(57) **CLAIM**

The ornamental design for a wall mounted button panel, as shown and described.

DESCRIPTION

FIG. 1 shows a front elevational view of a wall mounted button panel, with elements in dashed lines forming no part of the claimed design.

FIG. 2 shows an isometric projection of the wall mounted button panel of FIG. 1, with elements in dashed lines forming no part of the claimed design.

FIG. 3 shows a left side elevational view of the wall mounted button panel of FIG. 1, with elements in dashed lines forming no part of the claimed design.

FIG. 4 shows a right side elevational view of the wall mounted button panel of FIG. 1, with elements in dashed lines forming no part of the claimed design.

FIG. 5 shows a top plan view of the wall mounted button panel of FIG. 1, with elements in dashed lines forming no part of the claimed design; and,

FIG. 6 shows a bottom plan view of the wall mounted button panel of FIG. 1, with elements in dashed lines forming no part of the claimed design.

1 Claim, 4 Drawing Sheets
